SECATEURS

Edward A. Rogers, London, England, assignor to Wilkinson Sword Limited, London, England, a British company

Filed Jan. 10, 1966, Ser. No. 559

Term of patent 14 years

(Cl. D22—5)

FIGURE 1 is a perspective view of the front and one side of a pair of secateurs showing my new design;

I claim:

The ornamental design for secateurs, as shown.
